UNITED STATES PATENT OFFICE

GUY FRANKLIN BECKHAM AND CONNIE DUNCAN MORGAN, OF CROSBYTON, TEXAS

FURNACE DOOR-CARRIED FUEL BURNER

Application filed October 1, 1929. Serial No. 396,539.

This invention relates to improvements in gas burners for furnaces and particularly for supports therefor.

The primary object of the present invention is to provide a burner structure for use in furnaces of any type which is designed for burning low pressure fuel gas.

Another object of the invention is to provide a low pressure fuel gas burner for furnaces with improved means for supporting the burner in the furnace whereby the same may be swung out through the door of the furnace when the door is opened to facilitate the thorough cleaning out of the furnace fire box.

Still another object of the invention is to provide a gas burner structure for furnaces or the like whereby air may be supplied to the burner in such a manner that the efficient consumption of the fuel will take place with a minimum soot formation and without the creation of noise during operation.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawings:

Figure 1 is a view in front elevation of a furnace door constructed in accordance with the present invention showing the draft control doors associated therewith.

Figure 2 is a horizontal sectional view taken upon the line 2-2 of Figure 1.

Figure 3 is a vertical sectional view taken upon the line 3-3 of Figure 1.

Figure 4 is a face view of the gas burner plate, a portion of which is broken away to show the gas manifold therebehind.

Referring more particularly to the drawings wherein like numerals of reference indicate corresponding parts throughout the several views, the numeral 1 indicates gen-

erally the front wall of a furnace fire box, portions of the side walls thereof being indicated by the numerals 2.

The front wall 1 is provided with the door opening 3 and at each side of this opening there extends inwardly from the wall a shield wing 4.

Mounted upon the lugs 5 projecting from the face of the front wall of the furnace, by means of the hinge leaves 6, is a door 7, the leaves 6 being secured to the face thereof in the manner shown in Figure 1. This door is of a size to completely cover the opening 3 and has formed transversely therethrough in the central portion thereof the relatively wide slot 8 which is normally covered by a pair of supplemental doors each hinged as indicated at 10 adjacent opposite side edges of the main door 7 so that they may be brought into aligned position against the face of the main door to close the slot 8.

When the supplemental doors 9 are in closed position their free edges are in opposed relation as shown. Each of the supplemental doors 9 has a semi-circular recess 11 formed in the free edge thereof and when these recesses are brought into opposed position upon closing the doors a circular opening is formed through which a fuel supply pipe may be extended as will be hereinafter described.

Secured to the inner face of the door 7 adjacent the top thereof is a pair of transversely spaced hinge hooks 12 and directly beneath each of these hinge hooks 12 there is secured to the door a lower hinge hook 13.

To each of the hinge hooks 12 and 13 is pivotally attached one end of a burner supporting arm 14, the hinge shown being effected by forming the arms 14 with suitable apertures through which the hooks may be extended.

Supported by the other ends of the four arms 14 in the central portion of the furnace fire box is a burner structure indicated as a whole by the numeral 15. This burner structure comprises a rectangular shell which consists of a front wall 16 and the right angularly extending four side walls 17, the open side of the shell being directed toward the

furnace door when the burner is in operative position.

At the top and at the bottom of the shell there is attached a pair of hanger hooks, the pair in the top being indicated by the numerals 18 and the pair at the bottom by the numerals 19. As shown the hooks at the top of the burner shell are directed upwardly while those at the bottom are directed downwardly and each of the hooks of each pair has pivotal engagement in an inner end of one of the supporting arms 14 as is clearly shown in Figure 3.

The forward wall of the burner shell is provided with a plurality of relatively closely spaced apertures 20 and within the shell in relatively close proximity to the rear face of the wall 16 is a gas distributing manifold indicated generally by the numeral 21. This manifold as shown in Figure 4 is of rectangular design and may be provided with a single transverse central portion 22 connecting opposite ones of the side sections 23. This central section 22 of the manifold has connected therewith and opening therewith a fuel gas feed pipe 24 which extends through the aperture formed between the opposed edges of the supplemental doors 9 to the exterior of the furnace where it is connected by a removable coupling 25 with a feed pipe 26, the feed pipe being provided with a suitable valve 27 to cut off the flow of gas when disconnection of the coupling 25 is necessary.

The wall of each of the sections 22 and 23 of the gas manifold immediately adjacent the wall 16 of the burner are provided with discharge apertures 28 each of which is positioned to eject gas directly through an aperture 20 in the wall 16.

From the foregoing description it will be seen that the burner structure 15 is so supported that when the door 7 is in closed position it will be located in the proper position within the furnace. When a cleaning out of the furnace is necessary the entire burner structure may be removed with the swinging open of the door 7, the only preliminary operation necessary being the disconnection of the feed pipe 24 with the supply pipe 26 at the coupling 25 and the swinging open of the supplemental doors 9. When the main door 7 is swung back the necessary angular adjustment of the burner supporting arms 14 may be made to draw the burner through the furnace door opening 3.

In operation gas is fed into the manifold 21 and ejected through the apertures 28 through the adjacent apertures 20 of the shell wall 16, this passage of the gas drawing into the apertures 20 about the sides thereof sufficient air to form a completely combustible mixture. The supply of air to the burner is regulated by the doors 9 and the flow of air through the opening 8 controlled by these doors is directed to the burner by the wings

4 so that it will pass into the shell 15 and through the apertures 20 in the manner described. Some additional air will pass through the apertured plate 16 at points where a supply of gas is not provided, this air mixing with the gas inside the fire box and assisting in its combustion.

From the foregoing description it will be readily appreciated that there has been devised a new, novel and simple type of burner, which may be easily and inexpensively constructed, easily installed and readily shifted from operative to inoperative or vice versa as necessary.

Having thus described our invention, what we claim is:—

1. In a furnace structure, a fire chamber having a door opening, a door hingedly mounted before said opening, a fuel burner, supporting arms each hingedly attached to the inner face of the door and having hinge connection with said burner, means for conducting fuel to the burner through the door, said door having an air inlet opening therethrough, and draft control doors hingedly connected to the first mentioned door for closing said opening.

2. In a furnace structure having a fire chamber and a door opening therethrough, a door hingedly mounted before said opening and having a transverse slot therethrough, auxiliary doors mounted upon the first mentioned door and coacting to close said slot, said auxiliary doors having certain edges assuming opposed positions when closed, said edges being notched to form an aperture, a fuel burner, arms connecting the fuel burner with the inner face of the first mentioned door and supporting the same to swing in a horizontal plane, and a fuel supply pipe extending through the aperture formed between the auxiliary doors to the fuel burner.

3. In a furnace structure, a fuel burner comprising a rectangular shell arranged in vertical position and having a forward wall having a plurality of apertures formed therethrough and right angularly extending side walls, a gas supply manifold of polygonal formation arranged within the shell in close proximity to said forward wall and having a plurality of gas escape apertures each opening directly through an aperture in the adjacent wall, a fuel gas supply line leading to said manifold, and means for mounting the burner in position in the furnace.

4. In a furnace structure having a fire box and a door opening through one wall thereof, a door hingedly mounted before said opening and having a controlled draft opening therethrough, arm members each pivotally attached at one end to the inner face of the door, a burner structure comprising a shell having a forward wall and surrounding side walls, means for pivotally attaching the other end of each of said arms with one of

5 said side walls, said forward wall having a plurality of apertures therethrough, a gas supply manifold of polygonal formation having gas escape apertures in the wall thereof each directed toward an aperture in the shell wall, means for supplying fuel gas to the manifold, and air directing wings projecting inwardly at the sides of the furnace door opening.

10 5. In a furnace structure having a fire box and a door opening therefor, a door hingedly mounted to cover said opening, a fuel burner carried upon the inner face of the door to move therewith, a pivotal connection between the door and burner, and a fuel conducting pipe leading to the burner, said door having a transverse opening therein through which said pipe passes and in which it moves in a horizontal plane during relative movement between the door and burner.

15 6. In a furnace structure having a fire chamber and a door opening therefor, a door hingedly mounted to cover said opening, a fuel burner comprising an apertured shell body and a manifold within the body and provided with fuel escape apertures, a pair of up-turned hooks carried by said shell at the top thereof, a pair of down-turned hooks carried by the shell at the bottom thereof, a plurality of upwardly directed hooks carried by and upon the inner face of said door, supporting arms having apertures therethrough at the ends thereof each connecting a door carried hook with a hook carried by said shell, and means for supplying fuel to said manifold.

20 In testimony whereof we hereunto affix our signatures.
